(57) **CLAIM**

We claim the ornamental design for a display screen or portion thereof with animated graphical user interface, as shown and described.

DESCRIPTION

FIG. 1 is a first image for the display screen or portion thereof with animated graphical user interface, showing my new design;

FIG. 2 is a second image thereof;

FIG. 3 is a third image thereof; and,

FIG. 4 is a fourth image thereof.

The outermost broken lines in the figures show the display screen or portion thereof and the shorter broken lines in the figures show interior portions and text of the animated graphical user interface that form no part of the claimed design.

The appearance of the animated images sequentially transitions between the images shown in FIG. 1-4. The process or period in which one image transitions to another forms no part of the claimed design.

1 Claim, 4 Drawing Sheets
